UNITED STATES PATENT OFFICE.

DE WALT W. SMITH, OF LOUISVILLE, KENTUCKY, ASSIGNOR OF ONE-HALF TO NEAL V. TRAUTMAN, OF LOUISVILLE, KENTUCKY.

INDICATOR.

Application filed May 17, 1920. Serial No. 382,047.

To all whom it may concern:

Be it known that I, DE WALT W. SMITH, a citizen of the United States, residing at Louisville, in the county of Jefferson and State of Kentucky, have invented new and useful Improvements in Indicators, of which the following is a specification.

This invention relates to an indicator for use on cotton carding machines and the like, the principal object of the invention being to provide an indicator for indicating the displacement of the grinders upon the wires of the carding rollers.

Another object of the invention is to provide means whereby the indicator may be attached to the shafts of the grinders without changing the construction of said shafts in any way.

Still another object of the invention is to provide a cap for engaging each end of the grinder shaft with means for supporting all the parts of the indicator mechanism from said cap.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of a portion of a carding machine showing my invention applied thereto.

Figure 2 is a front view showing a pair of the carding cylinders and the grinders therefor.

Figure 3 is a view showing how the indicators are arranged in connection with the grinders and carding cylinder.

Figure 4 is an enlarged end view of one of the indicators.

Figure 5 is a sectional view through one of the indicators.

Figure 6 is a view looking towards the inner side of one of the indicators.

Figure 7 is a detail view of part of the grinding means.

In these drawings 1 and 2 indicate the carding cylinders which, as is well understood, are provided with a plurality of wires

for straightening the fibers of the cotton. In order to keep these wires of a uniform length, grinding mechanism is provided which is pressed into contact with the wires whenever necessary. This mechanism consists of a shaft 3 for each cylinder, each shaft being carried by a pair of slotted hangers 4 which are adjustably secured to the frame of the machine by the nuts and bolts 4', the bolts passing through the slots in the hangers. When the grinding means are to be used the nuts are loosened so that the grinding means can be pressed downwardly upon the wires but when the grinding means are not in use the hangers are raised until the lower ends of the slots engage the bolts and then the nuts are tightened to hold the parts in this position. As is well known the shafts 3 are provided with the spiral grooves 3'' to receive the projections 5' on the grinding 75 wheels 5 so that as the wheels are rotated they will also be moved back and forth upon the shafts. Each shaft is enclosed in a slotted casing 5'', the protection 5' extending through the slot 5''. Each shaft is provided with a pulley 3* and a pulley 5* is connected with each casing. These pulleys are connected with pulleys on a rotating part of the carding machine by the belts a so that both the shaft and the casing are 80 rotated to give the grinder wheel its rotary and reciprocatory movements. As the grinding means are of well known construction and form no part of my invention it is thought that further description thereof is unnecessary, it being seen that the grinding wheels will be moved back and forth along the shafts as they are being rotated, thus bringing them in contact with all the wires of the cylinders. To properly grind these wires 85 requires considerable skill on the part of the operator as he must know just how far he must move the grinding means to remove just the right amount of material to be removed from the wires. It is the object of 90 my invention to provide positive means for indicating the position of the grinding means relative to the axis of the wire cylinders and in carrying out my invention I provide indicator mechanism 6, adapted to be placed 100 upon each grinder shaft and having a part for engaging the cylinder so that the amount of displacement of the grinding means in order to place the grinding wheels in contact with the wires will be indicated by a 110

dial and finger forming part of the indicator mechanism. This mechanism consists of a cap 7 at each end of the grinding means having a hole therein to receive the reduced 5 end of the grinder shaft, the cap loosely engaging the grinder means so that it will not rotate therewith. This cap carries a tubular upright 8 through which the rod 9 passes. This rod is provided with an enlarged front 10 portion having an elongated opening 10 therein through which the small end of the shaft passes. The cap is provided with small fingers 11 which act as guides for said enlarged part of the rod. A casing 12 is carried 15 by the upper end of the tubular support 8 and this casing carries the dial 13 and a shaft 14 to which the finger 15 is secured. This shaft also carries a pinion 16 and the end of the rod 9 within the casing 20 is provided with a rack 17 which engages said pinion. A spring 18 engages the top of the rod and tends to hold the same in its lowest position with the finger at zero. The lower end of rod 9 carries an arm 19 which 25 has a roller 20 at its extremity.

When the grinder mechanism is to be used the bolts of the hangers are loosened and the caps are grasped by the hands of the operator and the entire device moved downwardly upon the cylinder with the rollers 30 20 engaging the edges of the cylinder, which are free of wires. Sufficient pressure is exerted to force the grinder wheel 5 against the wires of the cylinder and the shaft of 35 the grinder mechanism must be held perfectly level in order to cause the grinder wheel to grind all the wires the same length. This can be readily done by having the indicators registering the same amount of displacement, thus showing that each end of 40 the grinding mechanism has been moved the same amount as the other end. The pressure of each roller 20 upon the cylinder will cause the rod 9 to move upwardly and the extent 45 of this movement will be indicated by the finger being swung around the dial by the

engagement of the rack 17 with the pinion 16.

The indicators for the upper cylinder are provided with rollers 20 of greater diameter than such rollers on the indicators for the 50 lower cylinder.

It is thought from the foregoing description that the advantages and novel features of my invention will be readily apparent.

I desire it to be understood that I may 55 make changes in the construction and in the combination and arrangement of the several parts, provided that such changes fall within the scope of the appended claims.

What I claim is:—

1. A displacement indicator for the grinding mechanism of carding machines comprising a cap at each end of the grinding means, said cap rotatably receiving such grinding means, a guiding member carried by said cap and movable transversely of the axis of said cap, a dial supported by said guiding member, a finger associated with the dial, a rod slidably supported by said guiding member, an arm at the lower end 65 of said rod for engaging the carding cylinder and means for communicating the movement of the rod to the finger.

2. A displacement indicator for the grinding mechanism of carding machines comprising a cap at each end of the grinding means, said cap rotatably receiving such grinding means; a tubular upright carried by said cap and movable transversely of the axis of said cap; a dial casing at the upper 75 end of said upright, a shaft journaled in said casing, a finger on the end of said shaft cooperating with the dial, a pinion on the said last mentioned shaft, a rod passing through the upright and having a rack on its 80 upper end engaging the pinion, an arm extending at right angles to the lower end of the rod and a roller on said arm for engaging the carding cylinder.

In testimony whereof I affix my signature. 85

DE WALT W. SMITH.
